CLAIM

The ornamental design for a rectangular tent stake, as shown and described.

DESCRIPTION

FIG. 1 is a perspective view of a rectangular tent stake showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of the bottom plan view thereof;

FIG. 9 is the 9-9 cross-sectional view of FIG. 2 thereof;

FIG. 10 is the 10-10 cross-sectional view of FIG. 2 thereof; and,

FIG. 11 is the 11-11 cross-sectional view of FIG. 2 of a rectangular tent stake showing my design.

The broken lines shown in the figures are for the purpose of showing portions of the rectangular tent stake and form no part of the claimed design.

1 Claim, 6 Drawing Sheets
